DESIGN FOR A MAGNETIC BRACELET FOR HOLDING PINS AND SIMILAR ARTICLES

Fred H. Beyer, Lockport, N. Y.

Application April 20, 1938, Serial No. 76,649

Term of patent 7 years

To all whom it may concern:

Be it known that I, Fred H. Beyer, a citizen of the United States, residing at Lockport, in the county of Niagara and State of New York, have invented a new, original, and ornamental Design for a Magnetic Bracelet for Holding Pins and Similar Articles, of which the following is a specification, reference being had to the accompanying drawing, forming part thereof.

In the drawing the figure is a perspective view of the magnetic bracelet for holding pins and similar articles showing my new design.

I claim:—

The ornamental design for a magnetic bracelet for holding pins and similar articles, as shown.

FRED H. BEYER.
